UNITED STATES PATENT OFFICE.

CHARLES A. TURNER, OF MADISON, WISCONSIN, ASSIGNOR TO GISHOLT MACHINE COMPANY, OF MADISON, WISCONSIN, A CORPORATION OF WISCONSIN.

SYSTEM OF ELECTRIC-CURRENT DISTRIBUTION.

Application filed May 26, 1924. Serial No. 715,943.

To all whom it may concern:

Be it known that I, CHARLES A. TURNER, a citizen of the United States, residing at Madison, in the county of Dane and the State of Wisconsin, have invented a certain new and useful Improvement in Systems of Electric-Current Distribution, of which the following is a full, clear, concise, and exact description.

10. My invention relates to systems of electric current distribution and resides in the provision of improved means for supplying current to translating devices at low voltage from circuits furnishing current to other translating devices at high voltage. The system of my invention, for example, enables the operation of house bells by current supplied from commercial house lighting circuits.
15. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
20. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
25. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
30. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
35. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
40. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
45. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
50. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-
55. The system embracing my invention is inclusive of a source of current, a sectional resistance in bridge of the mains and including two sections in series, a relay having an energizing winding and a holding winding, one terminal of the energizing winding being connected by a conductor between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized, a second resistance in circuit with the other of these additional contacts and the other main, a third resistance in circuit with said added contact and the main with which this contact is connected, a supply conductor connected through the holding winding with the second resistance and the main with which the second resistance is connected when the relay is energized, a second supply conductor connected with the other main, the second and third resistances being connected serially and together in shunt of the sectional resistance when the relay is energized, a responsive device, and a switch for connecting the supply conductors through said responsive device and holding winding to bring the responsive device and holding winding in shunt of the third re-

sistance when this switch is closed and the relay is energized. The third resistance defines the maximum reduced voltage for the responsive device. This voltage may be varied below this maximum by an adjustable resistance in shunt of the third resistance.

In lighting systems it is common to ground one line circuit side or, if the system is a three-wire system, to ground the neutral conductor thereof. This grounding is effected at the generator. Fire underwriters' rules provide that instruments connected with such a grounded system be not themselves permanently grounded thereat, this precaution being taken to avoid electrolytic action.

The invention has for another of its objects the provision of a grounding switch which applies ground to the voltage reducing instrument while this instrument is disconnected and which switch serves, in conjunction with a fuse, to prevent the instrument from being reversely connected with the line or to remain in connection with the line after having once been rightly connected if the mains should thereafter be transposed. The low voltage circuit that supplies the low voltage translating device is thus guarded against the effects resulting from partial grounds accidentally applied to the side of such circuit that should be connected with the ungrounded side of the lighting circuit.

The accompanying drawings shows the preferred embodiment of the invention, Fig. 1 illustrating the preferred circuit arrangement in its idle condition and Fig. 2 illustrating the system in operation.

The supply mains 1 and 2 convey current impressed thereon at the higher pressure, say 110 volts, by the direct current or other generator 3 to supply incandescent lamps 3' or other load.

The supply main 1 is grounded at the grounded pole of said source. A sectional resistance is in bridge of the mains, this resistance having three sections 4, 5 and 6 in series, these resistance sections being preferably incandescent lamps. A relay 7 is in shunt of two of said resistance sections 5 and 6 taken together. The armature switch of the relay has a contact 8 connected with the grounded main and a grounded contact 9 that is connected with the grounded main through the aforesaid contact 8 and the

armature 10 when the relay is deenergized. The armature switch has an alternate contact 11 connected between the resistance sections 5 and 6 and a second alternate contact 12. A second relay has an energizing winding 13 and a holding winding 14, the aforesaid second alternate contact 12, being connected with one terminal of the energizing winding. The armature switch of the second relay has one contact 15 connected with the remaining terminal of said energizing winding, two additional contacts 16, 17 and also an added contact 18 which is connected with main 1 and connectable with said additional contacts 16, 17 when the second relay is energized. The additional contact 16 is connected with one terminal of the holding winding and is normal to the relay contact 15 and separable therefrom when the second relay is energized. A second resistance 19 is in circuit with the other additional contact 17 and the other main 2.

A third resistance 20 is in circuit with main 1 and said added contact 18 to define the maximum reduced voltage. An adjustable resistance 21, in shunt of the third resistance 20, serves to adjust the reduced voltage below the maximum. A supply conductor 22 is connected through this winding with the second resistance 19 and the main 2 with which the second resistance is connected when the second relay is energized. A second supply conductor 23 is connected with the other main 1, the second and third resistances 19, 20, being connected serially and together in bridge of the mains 1 and 2 when the second relay is energized. A normally open bridge 24 is connected between said supply conductors 22, 23, a responsive device 25 being in said bridge, as is also a switch 26 for closing the bridge. The holding winding and responsive device are preferably in series and together in shunt of the resistance 20 when switch 26 is closed and the second relay is energized.

When the energizing circuit 13, 15, 16, etc. of the second relay is broken at 15, 16, upon energization of this relay, the relay is maintained sufficiently energized to hold its armature, while the switch 26 is closed, by means of the holding winding 14 whose circuit is closed by the switch 26. When this switch is opened, the apparatus is restored from the used condition shown in Fig. 2 to the idle condition shown in Fig. 1.

In connecting the voltage reducing instrument with the mains, the terminals 27, 28 of the instrument should be respectively connected with the mains 1 and 2. If the voltage reducing instrument is reversely, wrongly, connected with the line, that is, has its terminals 27, 28 respectively connected with the mains 2 and 1, a fuse blowing circuit is established traceable from the grounded generator 3, through the main 1, and fuse

29 (which becomes blown), instrument terminal 27, the released armature 10, and the contacts 8 and 9 that are engaged by the released armature, to ground. The wrong connections have to be reversed and the blown fuse has to be replaced in order to maintain the connection of the instrument with the mains intact.

The instrument will be inoperative if it becomes reversely connected with the line due to the transposition of the mains of the lighting circuit following the closing of such circuit after it has been opened, since the fuse 29 would become blown to keep the circuit of the guarding magnet 7 from being closed. The translating device 25 cannot, therefore, be operative until the instrument has been correctly connected with the line and a new fuse supplied to replace the one that had become blown.

One set of values is noted upon the drawing. Others may be chosen.

Changes may be made without departing from my invention.

Having thus described my invention, I claim:

1. A system of electric current distribution including a source of current; supply mains in circuit with said source of current; a sectional resistance in bridge of the mains and including two sections in series; a relay having an energizing winding and a holding winding and having a conductor connecting one terminal of the energizing winding between said resistance sections, the armature switch of the relay having one contact connected with the remaining terminal of the energizing winding, two additional contacts, and an added contact connected with one main and connectable with said additional contacts when the relay is energized, one of the additional contacts being connected with one terminal of the holding winding and normal to the first relay contact and separable therefrom when the relay is energized; a second resistance in circuit between the other of these additional contacts and the other main; a third resistance in circuit between said added contact and the main with which this contact is connected; a supply conductor connected through the holding winding with the second resistance and the main with which the second resistance is connected when the relay is energized; a second supply conductor connected with the other main, the second and third resistances being connected serially and together in shunt of the sectional resistance when the relay is energized; a responsive device; and a switch in series with the responsive device and with the holding winding for connecting the supply conductors through said responsive device and holding winding, the responsive device and holding winding being in shunt of the third resistance when.

this switch is closed and the relay is energized.

2. A system of electric current distribution including a source of current having a grounded pole; supply mains in circuit with said source of current, one of these mains being grounded at the grounded pole of said source; a sectional resistance in bridge of the mains and having three sections in series; a relay in shunt of two of said resistance sections taken together and having a grounded contact that is connected with the grounded main by the armature switch of the relay when the relay is deenergized, an alternate contact between and connected with said two resistance sections, and a second alternate contact; a second relay having an energizing winding and a holding winding, the aforesaid second alternate contact being connected with one terminal of said energizing winding, the armature switch of the second relay having one contact connected with the remaining terminal of said energizing winding, two additional contacts, and an added contact connected with one main and connectable with said additional contacts when the second relay is energized, one of these additional contacts being con-

nected with one terminal of the holding winding and normal to the first, second relay contact and separable therefrom when the second relay is energized; a second resistance in circuit with the other of these additional contacts and the other main; a third resistance in circuit with said added contact and the main with which this contact is connected; a supply conductor connected through the holding winding with the second resistance and the main with which the second resistance is connected when the second relay is energized; a second supply conductor connected with the other main, the second and third resistances being connected serially and together in shunt of the sectional resistance when the second relay is energized; a responsive device; and a switch in series with the responsive device and with the holding winding for connecting the supply conductors through said responsive device and holding winding, the responsive device and holding winding being in shunt of the third resistance when this switch is closed and the second relay is energized.

In witness whereof, I hereunto subscribe my name.

CHARLES A. TURNER.
